LEONARD J. MARSHALL, OF WESTWOOD, NEW JERSEY, ASSIGNOR TO INTERNATIONAL COMBUSTION ENGINEERING CORPORATION, OF NEW YORK, N. Y., A CORPORATION OF DELAWARE

BENT TUBE BOILER

Application filed April 4, 1929. Serial No. 352,369.

- This invention relates to bent tube boilers such, for example, as Stirling boilers having mud and upper steam and water drums connected by banks of boiler tubes.
- 5 One of the primary objects of the invention is the provision of a boiler of the above type in which a maximum difference in gas temperature between the riser and downcomer banks is obtained.
- 10 Another object of the invention is the provision of improvements in the arrangement of the banks of tubes, the baffles and the steam heater location in boilers of the type above mentioned.
- 15 How the foregoing, together with such other objects as may hereinafter appear, or are incident to my invention, are realized, is illustrated in the accompanying drawing, wherein—
- 20 The figure is a more or less diagrammatic sectional elevation of a boiler constructed in accordance with my invention.
- The boiler illustrated is of the inclined type and comprises, in general, a mud drum 2, an upper front steam and water drum 3, a second steam and water drum 4 and a plurality of banks of tubes connecting the drums, in this instance three banks *a*, *b* and *c* being shown. A plurality of water circulators 5 and a plurality of steam circulators 6 are provided between the upper steam and water drums 3 and 4.
- The front bank *a* comprises a plurality of rows of tubes connecting the mud drum 2 with the front steam and water drum 3, the tubes of the rows being bent away from the drums at their upper and lower portions, and the major portion of their length being straight. The second bank *b* comprises a plurality of rows of tubes certain of which connect the mud drum with the front steam and water drum 3 and others of which connect the mud drum 2 with the second steam and water drum 4. In this instance I have shown the tubes of three of the rows of this second bank connecting into the front steam and water drum 3 and the remaining six rows are shown connected into the second steam and water drum 4. The rear bank *c* comprises a plurality of rows of tubes connect-
- ing the mud drum 2 with the second steam and water drum.
- In connection with the three rows of tubes of the second bank *b* which connect into the upper drum 3, it will be noted that they are slightly bent at their lower portions and from thence extend straight for the greater portion of their length and then bend toward the upper drum 3 for connection thereto. The amount of bend in the tubes of the rows just mentioned and in the tubes of the first bank is such as will provide a substantial space A between the front bank *a* and the second bank *b*, the space, vertically considered, being approximately in the shape of a rectangle, the long dimension of which is in a vertical direction.
- In the space thus provided I locate a steam heater, such as a reheat, superheater, or the like, which, by virtue of the rectangular shape of the space, may be of considerable size because, with such a space, the steam heater elements may extend for the major part of the length of the tube banks.
- A baffle 7 is associated with the front bank of tubes *a*, a baffle 8 is associated with the second bank *b* and a baffle 9 is associated with the rear bank tubes *c*. The baffle 7 is located toward the rear of the front bank *a*, and, as shown in the drawing, is located in back of the rear row of tubes and extends upwardly from the mud drum 2 to a point short of the front upper drum 3, thus providing a passage 10 above the baffle through which gases pass from the front bank to the space A between the first and second banks. The baffle 8 is located toward the front of the second bank of tubes *b*, and as here shown extends downwardly from the second upper drum 4 to a point short of the mud drum 2, thus providing a passage 11 below the baffle for the passage of gases from the space A to the second bank of tubes. In this instance the baffle 8 is composed of baffle members located in the space between the tubes of the first row of the bank *b*. The rearmost baffle 9 extends upwardly from the mud drum 2 to a point short of the second upper drum 4 and provides a passage 12 above it through which gases pass from the second bank *b* to the third

bank *c*. This baffle is preferably carried on the first row of tubes.

From the foregoing it will be seen that the gases of combustion from the combustion chamber (not shown) pass upwardly along the tubes of the front bank, cross over the tubes at their upper portions, enter the large space *A*, pass downwardly through this space and over the elements of the steam heater, then pass through the passage 11 to the second bank and upwardly over the tubes thereof to the passage 12, and finally pass downwardly over the tubes of the rear bank *c*.

Through the arrangement thus described it will be seen that there is a maximum difference in the temperature of the gases to which the riser or front bank tubes are subjected and the gases to which the downcomer tubes of the second bank leading from the drum 3 to the drum 2, are subjected, which secures effective circulation.

It is to be understood that if a reheater is located in the space *A*, as indicated in the drawing, then a superheater may be located at some other suitable point in the installation. An alternative arrangement would be one in which a superheater is located in the space *A* with a reheater located at some suitable point in the installation.

My invention is particularly useful in a high pressure installation having multi-stage turbines, for example one in which the furnace is provided with boiler tubes defining combustion space and in which a radiant type primary superheater for the high pressure steam is provided in the furnace and a convection type reheater for the low pressure steam is located in a cooler zone as shown in the drawing. By employing a convection type reheater located in the pass of the boiler between the first and second banks of tubes, the reheat temperature will not increase with decreased capacity and the reheater will not at any time be exposed to a sufficiently high temperature to damage the elements. Owing to the high pressure, the greater density and specific heat of the steam will afford ample protection of the radiant superheater elements at times of decreased capacity.

I claim:—

In combination, a bent tube boiler having a mud drum, upper steam and water drums and banks of tubes connecting said drums including a front bank, the tubes of which connect the mud drum and the front steam and water drum, and a second bank certain of the tubes of which connect the mud drum and a second steam and water drum and other tubes of which connect the mud drum and the front steam and water drum, said banks of tubes being so bent as to provide a substantial space therebetween for the major part of the longitudinal extent of the banks of tubes, a steam heater in said space, a rear

baffle for the front bank terminating short of the front steam and water drum, and a front baffle for the second bank terminating short of the mud drum and shielding all of the tubes of said second bank.

In testimony whereof I have hereunto signed my name.

LEONARD J. MARSHALL.
